(57) **CLAIM**

The ornamental design for a tachograph, as shown and described.

DESCRIPTION

FIG. 1.1 is a front view of the design for a tachograph for a vehicle such as a truck according to the present invention;

FIG. 1.2 is a partial top view showing the front end of the top of the tachograph of FIG. 1.1;

FIG. 1.3 is a partial bottom view showing the front end of the bottom of the tachograph of FIG. 1.1;

FIG. 1.4 is a side view showing the left side of the tachograph of FIG. 1.1;

FIG. 1.5 is a side view showing the right side of the tachograph of FIG. 1.1;

FIG. 2.1 is a front view of another design for a tachograph for a vehicle such as a truck according to the present invention;

FIG. 2.2 is a partial top view showing the front end of the top of the tachograph of FIG. 2.1;

FIG. 2.3 is a partial bottom view showing the front end of the bottom of the tachograph of FIG. 2.1;

FIG. 2.4 is a side view showing the left side of the tachograph of FIG. 2.1;

FIG. 2.5 is a side view showing the right side of the tachograph of FIG. 2.1;

FIG. 3.1 is a front view of another design for a tachograph for a vehicle such as a truck according to the present invention;

FIG. 3.2 is a partial top view showing the front end of the top of the tachograph of FIG. 3.1;

FIG. 3.3 is a partial bottom view showing the front end of the bottom of the tachograph of FIG. 3.1;

FIG. 3.4 is a side view showing the left side of the tachograph of FIG. 3.1; and,

FIG. 3.5 is a side view showing the right side of the tachograph of FIG. 3.1.

Portions of the tachograph which are not shown in the drawings are disclaimed.
